United States Patent

Des. 237,004
Patented Sept. 30, 1975

237,004

LAUNDRY AGITATOR OR SIMILAR ARTICLE

Gerald L. Blake, 29470 Everett, Southfield, Mich. 48076,
and Montgomery Ferar, 8775 Nadine, Huntington
Woods, Mich. 48070

Filed Jan. 11, 1974, Ser. No. 432,470

Term of patent 14 years

Int. Cl. D15—05

U.S. Cl. D49—1 C

FIG. 1 is a perspective view of a laundry agitator or similar article, showing our new design.

FIG. 2 is a top plan view.

FIG. 3 is a side elevational view.

We claim:

The ornamental design for a laundry agitator or similar article, substantially as shown and described.
